UNITED STATES PATENT OFFICE.

SAMUEL L. ALLEN, OF MOORESTOWN, NEW JERSEY.

DESIGN FOR A CULTIVATOR-FRAME.

SPECIFICATION forming part of Design No. 30,069, dated January 24, 1899.

Application filed May 10, 1897. Serial No. 635,941. Term of patent 7 years.

To all whom it may concern:

Be it known that I, SAMUEL L. ALLEN, a citizen of the United States, and a resident of Moorestown, county of Burlington, State of New Jersey, have invented and produced a new and original Design for a Cultivator-Frame, of which the following is a specification, reference being had to the accompanying drawing, which illustrates a perspective view of the said frame.

The leading feature of my design consists in the substantially T-shaped portion formed by projecting or radiating arms A B C, having elongated openings *a*, *b*, and *c*, respectively, the opening *a* extending for some distance past the line of the openings *b* and *c* in connection with the forwardly-projecting arms. The main body of each of the arms A B C is substantially rectangular in form and terminates in a rounded end *d*. The arms form part of a widened section *e*, in which are formed openings *f*, and from each side of the widened portion extend upwardly-projecting flattened sections *g*, which gradually

round and merge into right-angled sections *g'* and from thence continue in vertical planes to form inclined sections *g''*. From the sections *g* *g'* *g''* extend two gracefully-curved arms *i*, each having near its extreme end a rounded portion *k*, through which extends an opening *l*, and from thence to the extreme end the arms are contracted in width, as at *m*. At the juncture of the sections *g''* and the arms *i* are outwardly-projecting sections *n*, having on one face a central rib *o* at about the center of said sections and extending parallel to the sides thereof.

Having thus described my invention, what I claim, and desire to secure by Letters Patent, is—

The design for a cultivator-frame substantially as herein shown and described.

In witness whereof I have hereunto set my hand this 6th day of May, A. D. 1897.

SAMUEL L. ALLEN.
